UNITED STATES PATENT OFFICE

LAWRENCE BRADSHAW, OF BAINBRIDGE, NEW YORK

ABATING FOAMINESS IN GLUES

No Drawing.

Application filed February 20, 1930. Serial No. 430,141.

This process has for its object the abatement or prevention of foam in glues prepared from proteinous substances such as milk casein, vegetable seed meals and the like.

It is known that glues prepared from milk casein by the addition of lime, alkali salts and water, frequently have an undesirable tendency to foam, especially when the dry ingredients have been mixed together and kept in storage for a considerable time or exposed to unfavorable conditions of temperature and humidity. The foaming tendency exists in such glues, even if the casein has previously been coated with a mineral oil (as has been the practice for many years, for preventing action of the alkaline compounds on the casein during storage and shipment of the dry glue). Glues similarly prepared from vegetable proteinous substances, e. g. peanut meal and other meals of like character, frequently show this tendency in marked degree, not only in cases where the meals or glues have become stale in storage but also where fresh meals and chemicals are mixed together just before the water is added. Glues prepared from mixtures of milk-casein with one or more of the vegetable seedmeals of commerce may likewise exhibit a tendency to foam. Foamy glues, from whatever source, are usually deficient in mobility and cohesiveness, do not spread readily, and when applied to wood-veneers and the like give inferior joints.

The present invention relates to a method of abating or preventing the foaming tendency and improving the general character of such glues. It consists in adding to the wet glue (or preferably to the water in which the glue is to be dissolved) an oil which is practically insoluble in water, such as kerosene or other petroleum distillate less volatile than naphtha and lighter than an ordinary motor lubricant, or oil of cedar wood or other suitable oil, preferably together with a small amount of a phenolic substance such as phenol, cresol or their sodium compounds, sodium phenate and sodium cresylate. These oils act as foam-abaters, while the phenolic compound acts as a conditioning agent, im-

proving the physical character and cohesiveness of the glue, and may also be regarded as an auxiliary in the abatement of foam.

In my co-pending application, Serial No. 372,217 (filed June 19, 1929), I have disclosed the use of carbon tetrachloride and other chlorinated hydrocarbons for this same purpose. There is, however, an important difference between the effects of carbon tetrachloride and those of the compounds to be described in the present application, viz. its marked thickening action, whereby the viscosity of the glue is increased to an undesirable extent in some cases. I have found that when carbon tetrachloride is added to proteinous glues of the type described above, prepared from milk-casein and/or the seed-meals, a considerable thickening and impairment of mobility is produced, whereas the petroleum distillates and vegetable oils aforementioned produce no appreciable thickening or in some cases actually cause a thinning effect which is beneficial for some purposes. As an example of this action the comparative effects of carbon tetrachloride, cottonseed oil, or kerosene used in equal amounts in a given glue are cited below. This is a commercial glue containing about 35% of casein, 35% of peanut meal and appropriate amounts of lime and sodium salts, and is generally mixed with about $2\frac{1}{4}$ parts of water to 1 part of the glue base. For the purpose of this experiment about 225 parts of cold water are measured into a glue-kettle provided with a mixing device. To this is added 3 parts of the anti-foam substance selected, and the mixer is started. Without interrupting the stirring, 100 parts of the glue powder are added and after stirring for twenty minutes the glue is ready. The consistency of the glue at this period is determined in the Stormer viscosimeter, an instrument which consists of a cylinder rotating on a vertical axis between baffles in a cup filled with the glue. The number of rotations per minute is indicated on a dial. A viscous, sluggish glue will show few revolutions of the cylinder in unit time, while a thinner, mobile glue gives correspondingly higher viscosimeter readings. The readings obtained with this standard instrument, in

which the glue is maintained at an uniform temperature of 70° F., are given below. Two sets of readings were made, the first with the glues at 20 minutes after wetting and the second after 1 hour:

Compound added	Vascometer reading—revs. per minute	
	20 mins.	1 hour
None	23	15
Carbon tetrachloride	16	7
Kerosene	27	20
Cottonseed oil	21	13

15 In this example it will be seen that the viscosimeter readings for the normal glue are 23 and 15; those obtained with the glue in which carbon tetrachloride has been used are much lower, indicating considerable thickening; those with kerosene are substantially higher than normal, indicating thinning, while those with cottonseed oil are practically normal.

20 25 I have found that the most potent substances in the abatement of foam are those which produce the thinner glues, for example kerosene and the intermediate distillate obtained between the kerosene and light lubricating-oil fractions in petroleum refining, and oil of cedar wood. Effective also are some of the vegetable oils such as cottonseed oil, peanut oil, coconut oil, and in less degree linseed oil. Of the large number of organic 30 35 liquids which I have examined, comparatively few have proved to be highly effective in preventing foam in the casein and seed-meal glues referred to above. Many of them appear to have no anti-foam value. I have selected the substances named above as the best available at present for this purpose. While these substances may be used alone in the manner described, I prefer to add to them a small proportion, say from 2 to 10% by weight of 40 45 a phenolic compound such as carbolic or cresylic acid or the sodium salts of these.

50 The amount of petroleum distillate or vegetable oil used may vary from about 1% to 5% by weight of the glue-base employed, according to the character of the glue, while that of the phenolic compound may be from 0.1 to 1%. I do not, however, limit myself to these proportions. On an average glue, about 2% of the former and 0.2% of the latter have been found to give satisfactory results.

55 As an example of the preferred method of carrying out the invention the following is cited:

60 *Example I.*—100 parts of a glue base consisting of about 40% milk casein, 38% of peanut meal, 11% hydrated lime, 4% trisodium phosphate and 7% sodium fluoride, were 65 mixed with 225 pounds of cold water in a glue-kettle and stirred by means of a mechan-

ical agitator for about twenty minutes. The resulting product was a foamy glue of poor appearance, lacking in fluidity and cohesiveness, and in adhesive strength when applied to wood-joints. In another trial, about 2½ parts by weight of a 5% solution of cresylic acid in kerosene was mixed into the water before the addition of the glue-base, which was then added and the mixture stirred for twenty minutes as before. The glue thus obtained was much superior in mobility and cohesiveness to that produced from the same glue-base without the addition of the organic liquid, and gave a higher shear strength when applied to wood joints.

70 75 The oily liquid is preferably added to the water before the glue-base, but fairly satisfactory results may be obtained by adding it to the mixture of glue-base and water, just after wetting the glue base, i. e. in the initial stage of the mixing operation. The addition of the oily material (in the same proportion) to the dry glue base, to be subsequently mixed with the water does not appear to give nearly as good results and the addition of the oil to the dry glue base forms no part of the present invention. The main part of the "mixing" operation is done after the addition of the oily material.

80 85 It will be understood that I make no claim herein to the production in general of glues from milk-casein or vegetable seed-meal but only to improvements in the same which result from the abatement or prevention of foam in such glues by the use of one or more 90 of the substances described above. The expression "an oil selected from the herein described group consisting of mineral oil distillates and vegetable oils" is intended to cover the use of one or several of the oily materials mentioned in this specification. No claim, however, is made here to carbon tetrachloride.

95 I claim:

small percentage of a phenolic substance as described herein, thereafter adding the glue base to the water and stirring.

4. A process of abating foaminess in mixing a glue base with water, said glue base containing proteinous material, lime and alkali, which process comprises adding to the water a small percentage of kerosene and a small percentage of cresylic acid, thereafter adding the glue base to the water and stirring.

5. A process of abating foaminess in mixing a glue-base with water, said glue-base containing proteinous material, lime and alkali, which comprises adding to the mix immediately after the initial contact of the glue-base with the water and before any prolonged agitation has taken place, about 1 to 5% of an oil selected from the herein described group consisting of mineral oil distillates and vegetable oils, and thereafter stirring the mass to form a substantially homogeneous, fluid, spreadable glue.

6. A process of abating foaminess in glues which comprises incorporating an oil with the mixing water used with a dry glue base comprising alkali-soluble proteinous material and dry alkali, such oil being added separately from the said dry glue base, and being added prior to the main part of the operation of mixing said dry glue base with said water to form the liquid glue.

In testimony whereof I affix my signature.
LAWRENCE BRADSHAW.
